UNITED STATES PATENT OFFICE.

CHARLES KAUFMANN, OF NEW YORK, N. Y.

PAPER WREATH.

SPECIFICATION forming part of Letters Patent No. 315,795, dated April 14, 1885.

Application filed October 15, 1884. (Model.)

To all whom it may concern:

Be it known that I, CHARLES KAUFMANN, of the city, county, and State of New York, have invented a new and Improved Paper Wreath, 5 of which the following is a full, clear, and exact description.

The object of my invention is to provide a new and improved wreath made in imitation of a wreath of natural leaves.

10 The invention consists in a circular piece of paper, card-board, or analogous material, having its edges cut or punched out, the same as the contours of a wreath of natural leaves, and having its face printed in colors, in imitation 15 of a wreath of natural leaves, on which circular piece separate leaves are held at their stem ends.

Reference is to be had to the accompanying drawings, forming a part of this specification, 20 in which similar letters of reference indicate corresponding parts in both the figures.

Figure 1 is a face view of my improved paper wreath. Fig. 2 is a cross-sectional view of the same.

25 A circular piece, A, of paper, card-board, or analogous material, is punched or cut out, and on it the contours of leaves and berries, or leaves alone, or leaves and flowers, are printed, shaded, and colored and slightly embossed. 30 The edges of the circular piece are cut or punched to coincide with the edges or contours of a flat wreath made of natural leaves.

In the drawings a wreath of holly-leaves is 35 represented; but oak, maple, or other leaves may be represented. Separate leaves B, punched out of paper or card-board, are suit-

ably colored, and are provided at the stem ends with tongues C, which are passed through slots in the circular piece A and pasted to the back surface, whereby the leaves B are held 40 loosely on the surface of the piece A. As the free ends are a short distance from the surface of the piece A, they show heavier shadows and give the wreath more of the appearance of a wreath made of natural flowers. Flowers can 45 be secured on the wreath as well as leaves.

Having thus described my invention, I claim as new and desire to secure by Letters Patent—

1. In an imitation wreath, the combination, 50 with a circular piece of paper or card-board, of separate pieces secured on the face of the same, the face of the circular piece being printed in colors to represent a wreath of leaves or flowers, substantially as herein shown and described.

2. In an imitation wreath, the combination, 55 with the circular piece A, printed in colors, in imitation of a natural wreath, of separate leaves secured at their stem ends on the colored face of the piece A, substantially as herein shown 60 and described.

3. In an imitation wreath, the combination, 65 with the circular piece A, printed in colors, in imitation of a wreath, of the leaves B, having tongues C passed through slots in the piece A, and secured to the back of the piece A, substantially as herein shown and described.

CHARLES KAUFMANN.
